Patented Dec. 12, 1961

191,920

COMBINED HANDLE AND LATCH ACTUATING UNIT

Thomas K. Hale, Glendale, and Norman E. Roe, Sierra
Madre, Calif., assignors to Ekco Products Company,
Chicago, Ill., a corporation of Delaware

Filed Dec. 1, 1960, Ser. No. 63,091

Term of patent 14 years

(Cl. D50—7)

FIG. 1 is a front view of a combined handle and latch actuating unit embodying our new design.

FIG. 2 is a side view thereof.

FIG. 3 is a top plan view thereof.

FIG. 4 is a bottom plan view of the unit.

The undisclosed side of the article is substantially the same in appearance as the side shown.

We claim:

The ornamental design for a combined handle and latch actuating unit, as shown and described.
